[57] **CLAIM**

The ornamental design for a toy monorail vehicle, as shown and described.

DESCRIPTION

FIG. 1 is a front elevational view of a toy monorail vehicle showing my new design;

FIG. 2 is a left end elevational view thereof;

FIG. 3 is a right end elevational view thereof;

FIG. 4 is a rear elevational view thereof;

FIG. 5 is a top plan view thereof; and

FIG. 6 is a bottom plan view thereof.

Portions of FIG. 4 have been shown in fragment for ease of illustration.
